(57) **CLAIM**

The ornamental design for a rider simulation apparatus, as shown and described.

DESCRIPTION

FIG. 1 is a perspective view of a rider simulation apparatus showing my new design;

FIG. 2 is a front elevational view of the rider simulation apparatus;

FIG. 3 is a rear view of the rider simulation apparatus;

FIG. 4 is a right side elevational view of the rider simulation apparatus;

FIG. 5 is a left side elevational view of the rider simulation apparatus;

FIG. 6 is a top view of the rider simulation apparatus;

FIG. 7 is a bottom view of the rider simulation apparatus; and, FIG. 8 is a perspective view of the rider simulation apparatus. Elements in broken line are not claimed.

1 Claim, 6 Drawing Sheets
